STEVE WILLIAMS, OF SUGARITE, NEW MEXICO

SAND BOX AND BALL-FIELD MARKER

Application filed June 12, 1929. Serial No. 370,415.

This invention relates to new and useful improvements in devices for sanding tracks, marking baseball diamonds, tennis courts and the like.

5 An object of the invention contemplates the provision and arrangement of a housing.

Another object of the invention contemplates a discharge member for the receptacle.

An additional object of the invention embodies a guide for the discharge member to prevent displacement of the same from the rails of a track.

More specifically stated the discharge member may be so shaped as to facilitate 15 its employment as a scraper for removing ice and other matter from rails.

With the above and other objects in view, the invention further consists of the following novel features and details of construction, to be hereinafter more fully described, 20 illustrated in the accompanying drawing and pointed out in the appended claims.

In the drawing:

Figure 1 is a longitudinal sectional view 25 taken through the invention.

Figure 2 is a top plan view thereof.

Figure 3 is a horizontal sectional view taken through the receptacle with the cover plate applied.

30 Figure 4 is a sectional view taken on line 4-4 of Figure 1.

Figure 5 is a diagrammatic plan view of the invention in blank form.

Figure 6 is a fragmentary longitudinal 35 section view taken through the discharge member and illustrative of the provision and mounting of wheels upon the discharge member when it is desired to employ the device upon baseball diamonds and tennis 40 courts to mark the outline thereof and the bounds therefor.

Figure 7 is a fragmentary perspective view of the discharge member.

Referring to the drawing in detail 45 wherein like characters of reference denote corresponding parts, the invention as illustrated in blank form in Figure 5 of the drawing primarily resides in the provision of a plate, designated as at 10, and which 50 forms the bottom wall of a receptacle to be

formulated in a manner to be better understood in the further description of the invention. The side walls or panels 11 and 12 are bent upwardly from the side edges of the bottom plate and disposed in parallelism 55 as evidenced from the illustration of my invention in Figure 3 of the drawing. The rear wall 14 for the housing is distorted in the manner suggested for the side walls 11 and 12 but which in addition thereto is provided with a series of spaced openings 15 vertically arranged adjacent the ends thereof to accommodate fastening elements in the nature of rivets 16 passed through the apertures of ears 17 carried upon the rearmost 60 ends of the side wall portions 11 and 12.

The forward end wall 18 is carried upon the foremost end of the side wall 12 and bent therefrom at rightangles thereto and across the forward end of the receptacle. Tabs 19, 70 carried by and arranged at spaced intervals upon the lower or underside edge of the front wall 18, are rightangularly disposed thereon and projected within the interior of the receptacle to overlie the adjacent surface 75 portions of the bottom 10.

The meeting portions of the tabs 19 and the bottom wall 10 are apertured after the manner of the ears 17 to accommodate fastenings 20.

80 The discharge member, as mentioned in the foregoing, comprises an elongated strip, such as indicated at 21, and which is projected outwardly as a continuation of the forward edge of the bottom wall 10. Side 35 flanges 22, rightangularly disposed and upstanding from the strip 21, are adapted for connection at their innermost sides with ears 23 struck and bendably distorted from the opposed side edges of an opening 24 in the front wall 18 between the tabs 19.

The forward or protruding end of the channel as defined by the strip 21 and side flanges 22 therefor is partially closed by an end wall 25 bent upwardly from the forward end of the strip whereas a reversely disposed wall portion 26 is in turn bent from the uppermost end wall 25 to dispose the opposed side edges thereof in closed proximity to the adjacent faces of the side flanges 22 100

as shown in Figures 1, 6 and 7 of the drawing. That portion of the channel, aforementioned, between the wall portion 26 and the forward wall 18 and which will be hereinafter referred to as the skipper or scraper 5 is engaged at its point of deviation from the end wall 25 within a pocket 26' formed in the forward end of a cover plate 27. Ribs 26' carried by and outstanding from the side flanges 22 in oppositely disposed relation thereon are adapted for reception within channel or grooved portions 27' upon the side edges of the cover plate 27 and to provide a slide mounting therefor.

10 An insert, indicated generally as at 28' and of U-shape formation, is inverted for reception within the channel defined by the strip 21 and side flanges 22 therefor and which extends therein from the outer side 20 of the forward end wall 18 for an appreciable distance beneath the adjacent end of the cover plate 27 spaced from the end wall, to allow for sliding movement of the cover plate, whereby the channel may be completely enclosed.

15 The extremities 28 of the side flanges 22 projecting in parallelism from the end wall 25 of the strip 21, are extended upon the opposed sides of the ball of a rail for railway 30 rolling stock whereby the discharge member, in its entirety, will be held against wobbling motion. A lip 29, struck from and obliquely disposed from the strip 21, defines a discharge port 30 by means of which 35 the contents of the receptacle passing through the channel will be deflected and spread by the lip 29 precedent to subsequent discharge upon the upper side and ball of a rail. In the event it is desirous to employ the present invention for other purposes, such as for marking courts for tennis, fields for soccer and football, base ball diamonds and the like, it is necessary to elevate the end wall of the discharge 40 member for an appreciable height from the surface of the field and to this end, I employ an axle 31 having wheels 32 journaled upon the outermost ends thereof and between which lime or other material of a distinguishing color from the surface of the field 45 may be discharged between the wheels; the latter will provide a guard and guide for this purpose and the stripe or line will be evened by reason of the fact that any surplus material discharge will be initially deposited upon the inner circumference of the wheel tires.

It has been found through experiment that a regular coal shovel full of dry sand 50 will sand a piece of track approximating 800 feet in length.

If desired, handles may be provided upon the outer surfaces of the front and end walls of the receptacle to carry the device 55 from place to place or support same while

in operative use. In order that the sand and lime may be protected from the elements and to relieve condensation and lumping of the material, the upper portion of the receptacle is closed by a covering, designated 70 as at 33, and which is slidably mounted therein after the manner of the cover plate 27.

As noted from the enlarged fragmentary perspective view of the discharge means, 75 the reversely disposed wall portion 26 also curves beneath the lip 29 to serve as a guide for the latter when sliding upon rail heads.

The particular disposition of the wall portion 26 will also permit same to slide 80 over the joints of the rails irrespective of the width of the gap therebetween. The skipper or wall portion 26 may be also used to advantage in the scraping and removing of snow and ice from tracks.

85 Ears 34 struck from the strip 21 in the formation of the lip 29 and provision of the discharge opening 30, depending in space parallelism from opposite sides of the opening and which materially coact with the lip 90 29 in the dispensing of the receptacle contacts in the manner desired.

95 The invention is susceptible of various changes in its form, proportions and minor details of construction, and the right is here- in reserved to make such changes as properly fall within the scope of the appended claims.

Having thus described the invention, what is claimed is:—

100 1. A track sander comprising a receptacle having handles at the ends thereof, a discharge member of channel formation extended from one end of the receptacle and having communication with the interior thereof, and a lip struck and obliquely disposed from the bottom wall of the discharge member to spread the contents of the receptacle over the ball of a rail.

105 2. A track sander of the character described comprising a receptacle having handles at the ends thereof, a discharge member of channel formation carried by and having communication with the interior thereof, wall portions formed upon the outermost end of the discharge member and extended for an appreciable portion of its length, a casing for the discharge member extending between the wall portions and said receptacle, and guide portions formed 110 upon the side walls of the discharge member beyond the wall portions to prevent wobbling of the discharge member upon the head of a rail.

115 3. A track sander of the character described comprising a receptacle having handles at the ends thereof, a discharge member of channel formation carried by and having communication with the interior thereof, wall portions formed upon the out- 120

ermost end of the discharge member and extended for an appreciable portion of its length, a casing for the discharge member extending between the wall portions and said receptacle, guide portions formed upon the side walls of the discharge member beyond the wall portions to prevent wobbling of the discharge member upon the head of a rail, and a lip struck from the bottom wall of the discharge member at an inclination to effectively spread the contents of the receptacle as discharged across the head of a rail.

4. A track sander of the character described comprising a receptacle having handles at the ends thereof, a discharge member of channel formation carried by and having communication with the interior thereof, wall portions formed upon the outermost end of the discharge member and extended for an appreciable portion of its length, a casing for the discharge member extending between the wall portions and said receptacle, guide portions formed upon the side walls of the discharge member beyond the wall portions to prevent wobbling of the discharge member upon the head of a rail, a lip struck from the bottom wall of the discharge member at an inclination to effectively spread the contents of the receptacle as discharged across the head of a rail, and a skipper carried by the discharge member in advance of the lip.

In testimony whereof I affix my signature.
35 STEVE WILLIAMS.
